UNITED STATES PATENT OFFICE

2,186,045

PRODUCTION OF COLOR PHOTOGRAPHIC PICTURES

Wilhelm Schneider, Dessau, Germany, assignor, by mesne assignments, to Agfa Ansco Corporation, Binghamton, N. Y., a corporation of Delaware

No Drawing. Application February 2, 1939, Serial No. 254,235. In Germany February 5, 1938

11 Claims. (Cl. 95—6)

My present invention relates to the production of color photographic pictures.

It has been proposed to produce color photographic pictures by color development with use of dyestuff components having reactive methyl-ene-groups which in the development of a latent silver image by means of a developer containing a free amino-group, for example para-phenylenediamine, para-aminophenol or derivatives thereof, yield a dyestuff image in the place of the silver image. Such components are, for example, acetoacetic ester and its derivatives, pyrazolones, isoxazolones, para-nitrobenzylcyanide or malonitrile; of these pyrazolones and isoxazolones are principally used for producing red dyestuff pictures. The compounds of these last-named classes, however, do not fulfill all requirements in respect of variation of color tint in the production of multi-color pictures by the reversal process or copying process.

It is one object of my invention to provide a photographic material capable of yielding very beautiful purple-red tints by development in color.

25 A further object of this invention is to provide a photographic material one emulsion layer of which contains α -indolinone as the dyestuff component.

Another object is the provision of a photographic material which comprises an emulsion layer containing α -indolinone substituted at the nitrogen atom.

Yet another object is to provide a photographic material comprising an emulsion layer which contains α -indolinone substituted in the benzene nucleus.

A still further object is to provide a photographic material having an emulsion layer which contains α -indolinone substituted by alkyl groups, alkoxy groups, aryl groups, halogen, hydroxy groups or nitro groups.

45 Yet another object is the provision of a photographic material which contains in an emulsion layer α -indolinone the benzene nucleus of which being condensed with another cyclic ring system.

An additional object is to provide a photographic material comprising an emulsion layer which contains α -indolinone substituted by sulfo groups, carboxyl groups or other groups capable of enhancing the solubility of the compound.

A further object is to provide a photographic multi-layer material which comprises at least one emulsion layer containing substituted or un-50 substituted α -indolinone which is made fast to

diffusion in the binding agent of the emulsion by introducing particular groups.

Other objects of my invention will appear from the description following hereinafter.

The groups which impart fastness to diffusion 5 may be introduced, for example, by the methods described in the U. S. Patents 2,179,238, 2,178,612 and 2,179,244 and U. S. Patent applications 94,340 filed August 5, 1936, 159,518 filed August 17, 1937, 164,499 filed September 18, 1937, 166,832 10 filed October 1, 1937, 171,705 filed October 29, 1937, 175,285 filed November 18, 1937, 176,058 filed November 23, 1937 and 191,952 filed February 23, 1938.

The last named application describes components which contain in addition to a group rendering the component fast to diffusion a solubilizing group such as a carboxy group. The components are prepared by reacting the internal anhydride of a polybasic organic acid, such as 15 the anhydrides of maleic acid, succinic acid, pyro-tartaric acid and the like containing for example a long aliphatic chain i. e. of at least 5 carbon atoms such as octadecylene, isodecylene, iso-nonylene and the like with a color former 20 containing a reactive group such as an amino- or hydroxy group. The ring of the anhydride is thereby split in such a manner that one CO—group units with the reactive group and the other forms a carboxy group. As the color former 25 there may be used p-amino-aceto-acetic anilide, 4-amino-1-phenyl-3-methyl-5-pyrazolone, 1-amino-5-naphthol and the like. As the anhydride there may be used octadecylene succinic acid anhydride, α -dodecyl- α -hexahydrobenzene-35 pyro-tartaric acid anhydride and the like.

Also the nitrogen atom of α -indolinone may carry a radicle prescribed in one or other of the foregoing applications, for instance an undecyl group. Furthermore, as described in the specification of the U. S. Patent application Ser. No. 171,701 filed October 29, 1937, the molecule of the dyestuff component may be in the form of a chain. As explained in the mentioned specifications, radicles lending fastness to diffusion may 40 be introduced in known manner, for example, by way of amino-, hydroxy- or carbonyl-groups with formation of acid amides or esters. It is also possible to unite the radicle lending fastness to diffusion directly to the nitrogen without the 45 intermediary of an acid group or to introduce it as a substituent directly into the benzene nucleus.

The silver halide emulsion layers prepared with the aid of the aforesaid dyestuff components may 50

be cast in the form of single layers or in the form of multiple layers on one or both sides of a support to produce the multi-layer material, the layers being sensitized for different regions of the spectrum.

Alternatively, the photographic emulsions having different dyestuff components may be distributed in particles on a support. With the aid of this material screen pictures may be made.

10 The silver halide emulsion layers provided with the dyestuff components may be combined with other layers usual in photographic materials, for example filter layers, anti-halation layers, matting layers, backing layers. Again, these layers 15 may be combined with photographic layers in which by any other process, for example the silver bleaching out dyestuff process or the toning process, color images can be produced.

As a binding agent for the photographic emulsions gelatin or some other colloid usually employed in photographic practice may be used.

The following examples illustrate the invention:

Example 1

25 A compound of the following formula may be incorporated in a photographic layer:

The dyestuff component is produced in following manner: α -indolinone is dissolved in concentrated 40 sulfuric acid and nitrated by addition of 1 mol of sodium nitrate with cooling. The reaction product is precipitated by pouring out the mixture on ice and after recrystallizing from water is reduced with stannous chloride and hydro- 45 chloric acid. The tin is removed with hydrogen sulfide and the whole is concentrated by evaporation. The reaction product is then acylated with 1 mol of oleic acid chloride in pyridine. After 50 sulfonation with sulfuric acid containing 30 per cent SO3 with cooling a product easily soluble in water is obtained. This dyestuff component is then dissolved in a solution of sodium carbonate and added to a silver halide emulsion.

55 *Example 2*

A compound of the following formula may be incorporated in a photographic layer:

Stearylaniline is acylated with chloroacetyl chloride. The reaction product thus obtained is mixed with aluminium chloride and heated to 70 200° until the hydrochloric acid is completely removed. To the mixture there is added ice and the dyestuff component is obtained by extraction with ether. The component is then dissolved in methanol and the solution is added to a silver halide emulsion.

Example 3

1 mol of 6-amino- α -indolinone produced in the manner as described in Example 1 is caused to react with 1 mol of octodecylene-succinic acid anhydride. The product thus obtained of the following formula

is dissolved in a solution containing sodium carbonate and this solution is added to a photographic emulsion.

Example 4

20 1 mol of 6-amino- α -indolinone produced in the manner described in Example 1 is reacted with 1 mol of abietic acid chloride. The product thus obtained of the following formula

is dissolved in methanol and added to a photographic emulsion.

I claim:

1. A photographic silver halide emulsion containing a binding agent and a compound selected from the class consisting of α -indolinone and substituted α -indolinone, said compound containing in its molecule a group capable of making said compound fast to diffusion in said binding agent.

2. A photographic silver halide gelatin emulsion containing a compound selected from the class consisting of α -indolinone and substituted α -indolinone, said compound containing in its molecule a group capable of making said compound fast to diffusion in gelatin.

3. A photographic multi-layer material comprising at least one silver halide emulsion containing a binding agent and a compound selected from the class consisting of α -indolinone and substituted α -indolinone, said compound containing in its molecule a group capable of making said compound fast to diffusion in said binding agent.

4. A photographic multi-layer material comprising at least one silver halide gelatin emulsion layer containing a compound selected from the class consisting of α -indolinone and substituted α -indolinone, said compound containing in its molecule a group capable of making said compound fast to diffusion in gelatin.

5. A photographic multi-layer material comprising at least one silver halide emulsion layer containing a compound of the formula

6. A photographic multi-layer material com-

prising at least one silver halide emulsion layer containing a compound of the formula

7. A photographic multi-layer material comprising at least one silver halide emulsion layer 10 containing a compound of the formula

20 8. The photographic silver halide emulsion defined in claim 2 wherein the group capable of making said compounds fast to diffusion is an aliphatic radicle of high molecular weight.

9. The photographic silver halide emulsion defined in claim 2 wherein the group capable of making said compounds fast to diffusion is an aliphatic radicle of high molecular weight which is linked to the indolinone nucleus by a linkage 5 selected from the class consisting of a direct carbon to direct nuclear carbon linkage, an ester linkage and an acid amide linkage.

10. The photographic silver halide emulsion defined in claim 2 wherein the group capable of 10 making said compounds fast to diffusion is an aliphatic radicle containing from 18 to 22 carbon atoms.

11. The photographic silver halide emulsion defined in claim 2 wherein the group capable of 15 making said compounds fast to diffusion is an aliphatic radicle containing from 18 to 22 carbon atoms and having a solubilizing group selected from the class consisting of sulfonic acid and carboxylic acid groups.

20
WILHELM SCHNEIDER.
